Patented May 30, 1922.

68 C. B. Lord, Inventor.
S. Huffman, His Attorney.

UNITED STATES PATENT OFFICE.

CHESTER B. LORD, OF BATTLE CREEK, MICHIGAN.

INDICATING APPARATUS.

1,417,928.

Specification of Letters Patent. Patented May 30, 1922.

Application filed November 23, 1921. Serial No. 517,218.

To all whom it may concern:

Be it known that I, CHESTER B. LORD, a citizen of the United States of America, residing at Battle Creek, county of Calhoun, 5 State of Michigan; United States of America, have invented a certain new and useful Indicating Apparatus, of which the following is such a full, clear, and exact description as will enable any one skilled in the art to 10 which it appertains to make and use the same, reference being had to the accompanying drawings, forming part of this specification.

My invention relates to means for indicating graphically conditions existing at a 15 given time and as constructed for use in a manufacturing establishment, for example, comprises a chart and associated devices for indicating important facts with respect to 20 materials, tools, parts, fabrication or assembly of parts, orders, sales or the like. The particular embodiment of my invention to be hereinafter described constitutes a factory control chart for the production of the 25 parts of a machine or other device being manufactured.

The object of the invention is to produce a simple, inexpensive visual indicator of existing or impending conditions which may 30 be easily operated to show changes; which is divided into zones covering the jurisdictions of various employees and officials; which may be caused to indicate abnormal or exceptional conditions; and an indicating apparatus 35 in which erroneous indications cannot result from a break or other defect in the apparatus itself. Other objects and advantages of my invention will appear from the following more detailed description.

40 In the accompanying drawings, Fig. 1 is a front view of an indicating apparatus embodying my invention and Figure 2 is a cross sectional view on the line 2—2 of Figure 1.

45 The apparatus comprises a suitable frame 1 supporting a wire mesh 2 which mesh is divided visually into a plurality of parallel horizontally disposed zones, the limits of these zones being indicated by heavy lines 50 on the drawing but in practice may be conveniently indicated by having the portions of the mesh in the different or adjacent zones painted in contrasting colors. The number of zones employed will depend upon the 55 service to which the apparatus is being put,

the particular embodiment shown in the drawing having four zones A, B, C and D. Supported on the frame above the wire mesh is a recessed band 3 on which a strip of paper 4 is removably held. In the embodiment of my invention shown, this paper carries printed legends constituting the name or number or both of the various parts of a machine, such as a tractor for example, which is to be manufactured. Passing 60 through the wire mesh or through or over a suitable support at a point adjacent to these legends are one or more strings to the end of which at the rear of the apparatus are attached weights 5 and to the other end 70 indicators 6 of any suitable type such as colored beads. To the strings adjacent to the indicators are also attached hook members 7 which may be engaged with the wire mesh at any desired point and are held in 75 engagement by the action of weights on the strings tending to pull the indicator ends upward.

To prevent interference of the weights with each other in movement they may be 80 spaced by employing two or more spaced horizontally positioned supporting wires 8 over any one of which a selected number of the strings may be passed.

In the operation of the apparatus described for indicating the conditions existing at any particular time with respect to the manufacture of parts of a machine, an indicator will be positioned in the lowest zone only when an exceptional condition 90 occurs with respect to the manufacture of the part to which it applies which requires the attention of the general manager or production manager of the factory. When indicators are in zone C they show that the responsibility of bringing them up to zone 95 above is upon the production, order or purchasing departments, depending upon the character of the shortage of parts. Indicators in zone B show conditions requiring attention of subordinate employees and indicators in zone A show that the conditions with respect to the particular parts to which they apply, are normal. If a larger number of a given part has been completed than 100 is required under the plan of operation being following the indicator for this part is hooked over the upper edge of the band 3.

It will be noted that the unintentional release of an indicator or the breaking of a 110

string will cause the particular indicator to assume an abnormal position, calling attention to the defect and will not result in an erroneous indication.

5. It will be apparent that my improved indicating apparatus is applicable to a variety of particular uses such as for making indications of time, value, quantity, or jurisdiction and in general any use to which an indicating graph can be put, and is susceptible of structural modifications without departing from its fundamental principles of operation and I, therefore, do not intend that the scope of my invention be limited otherwise than set out in the appended claims.

Having fully described my invention what I claim as new and desire to secure by Letters Patent of the United States is:

1. In an indicating apparatus, the combination with means forming a surface divided into parallel zones, movable indicators, means for retaining the indicators in desired position on said surface, and means adapted to return the indicators to predetermined positions when released from the retaining means.

2. In an indicating apparatus, the combination of means forming a surface divided into parallel zones, indicators, each movable into any selected zone, means for retaining the indicators in desired position on said surface, and means adapted to return the indicators to predetermined positions when released from the retaining means.

3. In an indicating apparatus, the combination with means forming an indicating surface, movable indicators provided with means tending to move them to predetermined positions, and means for retaining any indicator in other positions on said surface.

4. In an indicating apparatus, the combination of a frame, a plurality of spaced wires supported thereby, means dividing the said series of wires into a plurality of parallel zones, indicators provided with retaining means adapted to engage said wires, and means adapted to return the indicators to predetermined positions when released from the wires.

5. In an indicating apparatus, the combination of a frame, a plurality of spaced parallel vertically disposed wires crossed by a plurality of spaced parallel horizontally disposed wires, means dividing the said series of wires into a plurality of horizontal zones, indicators provided with retaining means adapted to enter spaces formed be-

tween the horizontal and vertical wires, and means adapted to return the indicators to predetermined positions when released from the wires.

6. In an indicating apparatus, the combination of a section of wire mesh, indicators provided with means for engaging the openings of the mesh, weights attached to the indicators by means of strings, and string supporting means above the weights, and engaging the strings between the weights and indicators.

7. In an indicating apparatus, the combination of a section of wire mesh suitably divided into parallel horizontally extending zones, indicators provided with means for engaging the openings in the mesh and weights attached to the indicators by means of strings passing through the upper portion of the mesh.

8. In an indicating apparatus, the combination of a section of wire mesh, indicators provided with means for engaging the openings of the mesh, weights attached to the indicators by means of strings, string supporting means above the weights, and engaging the strings between the weights and indicators, and means for spacing the weights to prevent interference in movement.

9. In an indicating apparatus, the combination of means forming an indicator receiving surface having indicating subdivisions, means above said surface carrying legends, and indicators having attached means extending to positions adjacent to said legends.

10. In an indicating apparatus, the combination of means forming an indicator receiving surface, means above said surface carrying printed legends, indicators having attached strings extending to points adjacent to said legends, means for attaching said indicators to the indicator receiving surface, and means for supporting said indicators at points above said legends.

11. In an indicating apparatus, the combination of means forming an indicating surface and provided with a plurality of openings one above another, indicators provided with means for engaging said openings, weights attached to the indicators by means of strings, and string supporting means above the weights and engaging the strings between the weights and indicators.

In testimony whereof, I have hereunto set my hand and affixed my seal.

CHESTER B. LORD. [L.S.]
